UNITED STATES PATENT OFFICE

136,965

DESIGN FOR A JODHPUR

Glenn C. Wharton, Omaha, Nebr.

Application October 29, 1943, Serial No. 111,531

Term of patent 14 years

To all whom it may concern:

Be it known that I, Glenn C. Wharton, a citizen of the United States, residing at Omaha, in the county of Douglas and State of Nebraska, have invented a new, original, and ornamental Design for Jodhpur, of which the following is a specification, reference being had to the accompanying drawing, forming part thereof.

Figure 1 is a perspective view of one side of a jodhpur showing my new design.

Figure 2 is a perspective view showing the other side of the same.

I claim:

The ornamental design for a jodhpur, as shown.

GLENN C. WHARTON.
